FERDINANDO CERBO, OF PROVIDENCE, RHODE ISLAND.

URETHROSCOPE OR ENDOSCOPE.

1,139,015.

Specification of Letters Patent. Patented May 11, 1915.

Application filed December 10, 1914. Serial No. 876,552.

To all whom it may concern:

Be it known that I, FERDINANDO CERBO, a subject of Italy, residing at Providence, in the county of Providence and State of Rhode Island, have invented a new and useful Improvement in Urethroscopes or Endoscopes, of which the following is a specification.

My invention has reference to an improvement in urethroscopes and more particularly to an improvement in the urethroscopes patented to me September 12, 1911, No. 1,003,232 and November 12, 1912, No. 1,044,348.

The improved instrument forming the subject of this application relates, as above stated, to urethroscopes or endoscopes and analogous tubular instruments adapted to be inserted into the urethra or other channels, said instruments being provided at their lower or distal end with means for temporarily and interruptedly dilating the urethral or other passage and as employed by physicians, for the purpose of making visual examinations as well as treating the urethral channel or other cavities, and to facilitate the use of other instruments in the urethral passage or other channels.

There are still disadvantages or objections to instruments or urethroscopes of the character above referred to; that is to say, they support on the lower or distal end a plurality of dilators jointed to the outer tube and laterally and angularly movable, said dilators being provided each with a back terminal or hook to form a hinge pivot with the outer tube and an inwardly extending extension or finger on their inner face to engage the inner tube through a corresponding opening in the end of the inner tube.

The outer tube has a longitudinal inside groove for an electric wire whose terminal is at the hinge joint of the dilators. An electric lamp is inclosed in a metal casing on the inner side of a dilator and the electrical contact is made between the lamp and the terminal of the wire at the hinge pivot of the dilator. Moving the inner tube downwardly causes the dilators to swing outward or open and energizes the electric lamp, and moving the inner tube in the reverse direction causes the dilators to close and cuts out the lamp; the result being that the dilators will be sharply angular and distressful on account of a comparatively long distension of the dilated tissues without any benefit whether relating to visual examina-

tions or treatment, because the lower direct area of vision obtained by the lower ends or apices of the dilators is only required for all practical purposes. The depressions projecting inside of the inner tube causes partial loss of vision field, the projecting fingers are a material impediment to the free use of applicators, being liable to catch cotton swabs, or to the free use of other treatments or operating instruments. The electric contact between the wire terminal and the lamp at the hinge is impractical, as the contact of liquid at this point will cause dispersion of the electric current and the light will go out and finally insanitary conditions at the hinge joint of the dilators are detrimental and the instrument is costly to manufacture.

The object of my invention is to improve the construction of a urethroscope whereby a more simple, practical, less expensive and self contained instrument is produced and in which the disadvantages or objections above referred to are wholly eliminated.

My invention consists in the peculiar and novel construction of a urethroscope, said urethroscope having details of construction as will be more fully set forth hereinafter and claimed.

Figure 1 represents a side view of my improved urethroscope, somewhat enlarged, showing the dilators in their normal or closed position in full lines and in an expanded position in dotted lines. Fig. 2 is a still further enlarged longitudinal sectional view taken on line 2 2 of Fig. 1 with the central portion broken away. Fig. 3 is an enlarged transverse sectional view taken on line 3 3 of Fig. 1. Fig. 4 is a partial, longitudinal central sectional view, still further enlarged, showing the dilator arms normally closed and the levers for opening and closing the same. Fig. 5 is an enlarged side view of the distal end portion of the inner tube. Fig. 6 is an enlarged end view of the distal end of the inner tube. Fig. 7 is an enlarged longitudinal detail sectional view showing the electrical connections for the lamp and the removable shell used over the lamp when forceps' operations on foreign bodies are to be performed, and Fig. 8 is an enlarged longitudinal detail sectional view showing the electrical connection for the battery.

In the drawings, Fig. 1 represents my improved urethroscope as a whole, the same consisting essentially of the relatively sta-

tionary outer tube 9, the non-revoluble but longitudinally movable inner tube 10 in circumferential and longitudinal contact with the outer tube, as shown in Fig. 2, a plurality of laterally movable comparatively short dilator arms 11 11, forming an integral extension of the end of the outer tube, an operating member 12, a removable telescope member 13 on the head end and an electric light bulb 14 in the inner or dilator end of the instrument. All of the above named elements, so far as possible may be made of German silver or other suitable material.

15 The diameter and length of the outer tube 9 may be of any suitable dimensions, such for example as will permit the instrument to be readily inserted into the urethral passage. The end portion of the outer tube which

20 may be termed the outer or head end is provided with a slightly enlarged cylindrical head 15, having internal screw-threads 16, a short internal longitudinal slot 17, a right angle tubular boss 18 having an inlet duct

25 19, and a right angle tubular boss 20 for the electrical connection of an electric battery. The inner tube has an externally screw-threaded head end 21, a bearing ring 22, a spline 23, which enters the slot 17 in the

30 head and while allowing longitudinal movement of the inner tube prevents said inner tube from turning on its axis; an elongated inlet opening 24 in the side underneath the inlet duct 19, a plurality of openings 25 25, adjacent the inner end of the tube and a groove 26 which extends lengthwise in the outside of the inner tube from the boss 20 to the inner end of the tube for the small tube carrying the electric light wire.

35 40 The inner end of the outer tube 9 is formed into a plurality of comparatively short dilator arms 11 11, which are formed integral with the end of the tube. These dilator arms may be straight or curved and when closed form a cone shaped apex or inner end on the instrument. The free or apex ends of the dilator arms may be slightly enlarged so that, when the dilator arms are in their

45 50 closed positions a longitudinal space is formed between the adjacent edges or sides of each pair of dilator arms. A miniature ring 27, is secured to the inner face of each dilator arm 11 and a lever arm 28 is pivotally secured at one end to the ring 27 and at its opposite end to the end of the inner tube 10, through an opening 25 in the end of the tube, thereby operatively connecting the dilator arms 11 11 with the inner tube, as

55 60 shown in Figs. 2 and 4.

The operating member 12 is in the form of an externally screw-threaded sleeve in screw-threaded engagement with the internal screw-threads 16 in the head 15 and has a knurled flange 29. The operating member

12 is rotatably secured to the head end of the inner tube 10 by the bearing ring 22 and a screw-threaded collar 30, as shown in Fig. 2.

The telescope member 13 is in the form of a short tube 31 internally screw-threaded and adapted to screw over the screw-threaded end 21 of the inner tube 10, an enlarged end portion 32 carrying a magnifying lens 33 and an outlet pipe 34 leading at right angles to the tube 31. A screw fitting 35 is detachably secured in the inlet duct 19 from which a rubber pipe, not shown, may lead to a source of fluid supply, not shown and a rubber pipe, not shown, may be secured to the outlet pipe 34, and extend downward to a receiving receptacle, not shown.

The electric light bulb 14 has one pole connected to an insulated central contact point 36 and the other pole connected to a screw-threaded metal end 37 which screws into a screw-threaded end 38 of a small metal tube 39 which extends from the lamp 14 to the boss 20, in the groove 26, in the inner tube 10. An insulated wire 40 extends through the tube 39, one end 41 being secured in an insulating block 42 in a position to form an electric contact with the contact point 36 of the lamp and the other end 43 being secured in an insulating block 44 in the boss 20 in a position to form an electrical contact with one pole 45 of an electric battery 46, the other pole 47 being formed by the metal screw-threaded end of the battery which screws into the boss 20, the metal of the instrument forming the other electrical connection back to the lamp. Only the necessary portion of the battery 46 is shown, to illustrate the electrical connection, the balance of the battery being broken away. A metal light casing 48, open at the ends is used over the lamp only when forceps operations are to be performed.

By means of this improved construction the urethroscope when inserted, as in use, may be easily and quickly manipulated so as to accurately and positively operate the dilator arms simultaneously to the desired extent, thereby correspondingly enlarging that portion of the urethral passage and temporarily producing a complete dilation of the folds of the cavity, preparatory to examinations, forceps operation, irrigation or other operations.

In the use of my improved urethroscope the instrument first sterilized is inserted into the urethral passage or other channels to the extent desired followed by turning the operating member 12 to the right thereby correspondingly moving the inner tube 10 lengthwise, when through the lever arms 28 28 on the end of the tube connected with the dilator arms, the dilator arms are expanded or opened as shown in dotted lines in Fig. 1. The electric light 14 is now lighted by turning the battery 46, and bringing the contact

5 pole 45 into electrical contact with the end 43 of the wire 40, thereby closing the circuit. The physician may then make a visual examination or inspection of the thus acted upon parts. When irrigating, the remedial liquid flows through the fitting 35, the inlet duct 19, the opening 24, through the bore of the inner tube 10 to the enlarged portion of the urethra, then flowing back through the 10 bore of the inner tube, as in the case of retrojector and escaping out through the outlet pipe 34, the remedial liquid is thus kept entirely out of contact with the external portions of the human body. At the completion 15 of the operations, the battery 46 is turned in a reverse direction thereby breaking the contact between the pole 45 and the wire end 43, and putting out the lamp 14. The member 12 is then turned to the left thereby retracting 20 the inner tube and bringing the dilator arms 11 back to their normal closed positions. The instrument is then removed from the urethra or other channel. The telescope member 13 may be easily removed 25 by unscrewing the same from the end of the inner tube 10 for the insertion of other instruments into the urethroscope. The dilator or apex end of the instrument is now externally smooth and free from joints, the 30 electrical connections to the lamp are positive in their operations and a more sanitary and perfect operating instrument is produced than has heretofore been done.

Having thus described my invention I 35 claim as new:—

1. In a urethroscope, an outer tube, a plurality of comparatively short dilator arms formed integral with the outer tube and forming when closed a cone-shaped end on the outer tube, each dilator arm being so shaped that when in the closed position a longitudinal space is formed between each pair of dilator arms, an inner tube in contact for its entire length with the outer tube, 40 means for operatively connecting the apex end of the inner tube with each dilator arm, means for holding the inner tube from turning on its axis and means for reciprocating the inner tube.
2. In a urethroscope, an outer tube, a plurality of comparatively short dilator arms formed integral with the apex end of the 45 outer tube, said dilator arms having a pointed end, a comparatively wide central portion and a comparatively narrow base, an inner tube in surface contact with the outer tube, a lever arm operatively connected with each dilator arm and with the apex end of the inner tube, means for holding the inner tube from turning on its axis and means for reciprocating the inner tube.
3. In a urethroscope, an elongated outer tube, a plurality of comparatively short dilator arms formed integral with the apex end of the outer tube, an elongated inner tube 55 in surface contact with the outer tube, a ring on the inner face of each dilator arm, a lever arm operatively connected with each ring and with the apex end of the inner tube through an opening in the end of the inner tube, means for holding the inner tube from turning on its axis and means for reciprocating the inner tube.
4. In a urethroscope, an elongated outer tube, a plurality of comparatively short dilator arms formed integral with the apex end of the outer tube, an elongated inner tube 60 in surface contact with the outer tube, a lever arm operatively connected with each dilator arm and with the apex end of the inner tube through an opening in the end of the inner tube, means for holding the inner tube from turning on its axis and means for reciprocating the inner tube.
5. In a urethroscope, an elongated outer tube, a plurality of comparatively short dilator arms formed integral with the apex end of the outer tube, an elongated inner tube 65 in surface contact with the outer tube, a lever arm operatively connected with each dilator arm and with the apex end of the inner tube through an opening in the end of the inner tube, means for holding the inner tube from turning on its axis and means for reciprocating the inner tube.
6. In a urethroscope, an elongated outer tube, a plurality of comparatively short dilator arms formed integral with the apex end of the outer tube, an elongated inner tube 70 in surface contact with the outer tube, a lever arm operatively connected with each dilator arm and with the apex end of the inner tube through an opening in the end of the inner tube, means for holding the inner tube from turning on its axis and means for reciprocating the inner tube.
7. In a urethroscope, an elongated outer tube, a plurality of comparatively short dilator arms formed integral with the apex end of the outer tube, an elongated inner tube 75 in surface contact with the outer tube, a lever arm operatively connected with each dilator arm and with the apex end of the inner tube through an opening in the end of the inner tube, means for holding the inner tube from turning on its axis and means for reciprocating the inner tube.
8. In a urethroscope, an elongated outer tube, a plurality of comparatively short dilator arms formed integral with the apex end of the outer tube, an elongated inner tube 80 in surface contact with the outer tube, a lever arm operatively connected with each dilator arm and with the apex end of the inner tube through an opening in the end of the inner tube, means for holding the inner tube from turning on its axis and means for reciprocating the inner tube.
9. In a urethroscope, an elongated outer tube, a plurality of comparatively short dilator arms formed integral with the apex end of the outer tube, an elongated inner tube 85 in surface contact with the outer tube, a lever arm operatively connected with each dilator arm and with the apex end of the inner tube through an opening in the end of the inner tube, means for holding the inner tube from turning on its axis and means for reciprocating the inner tube.
10. In a urethroscope, an elongated outer tube, a plurality of comparatively short dilator arms formed integral with the apex end of the outer tube, an elongated inner tube 90 in surface contact with the outer tube, a lever arm operatively connected with each dilator arm and with the apex end of the inner tube through an opening in the end of the inner tube, means for holding the inner tube from turning on its axis and means for reciprocating the inner tube.
11. In a urethroscope, an elongated outer tube, a plurality of comparatively short dilator arms formed integral with the apex end of the outer tube, an elongated inner tube 95 in surface contact with the outer tube, a lever arm operatively connected with each dilator arm and with the apex end of the inner tube through an opening in the end of the inner tube, means for holding the inner tube from turning on its axis and means for reciprocating the inner tube.

In testimony whereof, I have signed my name to this specification in the presence of two subscribing witnesses.
